UNITED STATES PATENT OFFICE.

OSCAR JUNGGREN, OF SCHENECTADY, NEW YORK, ASSIGNOR TO GENERAL ELECTRIC COMPANY, A CORPORATION OF NEW YORK.

MIXED-PRESSURE TURBINE.

1,085,133.

Specification of Letters Patent. Patented Jan. 27, 1914.

Application filed August 9, 1913. Serial No. 733,978.

To all whom it may concern:

Be it known that I, OSCAR JUNGGREN, a citizen of the United States, residing at Schenectady, county of Schenectady, State of New York, have invented certain new and useful Improvements in Mixed-Pressure Turbines, of which the following is a specification.

This invention relates to elastic fluid turbines, and especially to those in which provision is made for operating the machine not only by high pressure steam but also by low pressure steam exhausting from some engine or appliance using high pressure steam. In these so-called mixed pressure units, it is important that the high pressure part shall be as efficient as an ordinary high pressure turbine. In order to accomplish this and yet not make the machine too expensive, or too inefficient by having too many high pressure wheels running idle, when operating under low pressure conditions, it is necessary to utilize as many as possible of the wheels for both high pressure and low pressure operation.

The object of my invention is to provide a mixed pressure turbine which will give a good efficiency for both high and low pressure operating conditions. The machine comprises one two-row bucket wheel used only for high pressure steam, and a plurality of single-row bucket wheels used wholly for low pressure steam. When the machine is operating low pressure, the high pressure wheel runs idle, but it offers very little resistance as it revolves in the first of the low pressure stages, where the gage pressure is at or below that of the atmosphere. The low pressure steam enters a chamber at one end of the machine, from which it flows to the low pressure wheels through passages outside of the high pressure wheel chamber. The high pressure steam enters through a number of separately-governed valves and goes through nozzles to the double wheel, which is preferably a little smaller in diameter than the single low pressure wheels. The exhaust from the high pressure wheel goes to a special set of nozzles arranged in side of and concentric with the first stage low pressure nozzles and delivering said exhaust steam upon the buckets of the first stage low pressure wheel. A hand-operated valve opens communication between the low pressure admission chamber and the

chamber in which the high pressure wheel is housed, in order to utilize the aforesaid special nozzles for low pressure operation in case a deficiency in low pressure steam or in vacuum occurs.

In the accompanying drawings, Figure 1 is a side elevation, partly in section, of a turbine embodying my improvements; Fig. 2 is a sectional end elevation; Fig. 3 is a detail section through the hand-operated connecting valve; Fig. 4 is an elevation of the thickened portion of the casing containing the passages and ports which supply steam to the first stage low pressure wheel; Fig. 5 is an elevation of a part of the special nozzles which receive the steam from said passages and ports; Fig. 6 is a cross section of a duplex bucket for use on the first low pressure stage wheel; and Fig. 7 is a longitudinal section of three such buckets.

The turbine illustrated is a horizontal machine of the Curtis type having a shaft 1 extending through a casing 2. On this shaft is the bucket wheel 3 having two rows of buckets 4 coöperating with the stationary intermediates 5. This is the high pressure wheel and its stage is separated by the diaphragm 6 from the first of the low pressure stages in which the one-row bucket wheels 7 are located. The high pressure steam is supplied to the machine by the main 8 and its admission to the wheel 3 is regulated by a plurality of nozzle valves 9, each controlling a separate passage 10 leading to a set of nozzles 11 covering a portion of the circumference of the wheel 3. The nozzle valves are operated in succession by any suitable valve gear, such for instance as levers 12 actuated by cams 13 on a shaft 14. The passages 10 are cored out in a segmental bridge 15, L-shaped in cross section, which is integral with the inner web 16 and side wall 17 of one head of the turbine casing; said head being hollow to form a receiving chamber 18 for the low pressure steam. The nozzles 11 project from the inner face of the web 16.

The low pressure steam is supplied through a conduit 19 controlled by a double-seat stop valve 20 and a butterfly throttle valve 21; this butterfly valve and the high pressure valve gear being controlled by the speed governor 22 by mechanism not shown. The conduit 19 communicates with the chamber 18, and the low pressure steam is distributed therein to a plurality of openings 23 ar-

ranged around the circumference of the web 16 and delivering steam to passages 24 leading to the nozzles 25 of the first low pressure stage, arranged just in front of the dia-
 5 phragm 6. The passages 24 are cored in the outside wall of the casing 2, which is made very thick for this purpose around the high pressure stage chamber.

The nozzles 25 are secured to a flange 26 of the casing, and are composed of two por-
 10 tions; an outer portion having nozzles de-
 signed to utilize low pressure steam and an inner concentric portion designed for the exhaust steam coming from the high pres-
 15 sure wheel 3, which reaches said nozzles by way of ports 27 cored in the flange 26, near the joint between said flange and the dia-
 phragm 6. The two parts of the nozzles 25 are separated by a continuous partition 28,
 20 so that the two currents of steam cannot in-
 termingle; each part of the nozzle being specially designed to give the best efficiency with the amount and pressure of the partic-
 25 ular kind of steam supplied to it. Both parts of the nozzles 25 deliver the steam to buckets on the first low pressure stage wheel 7. These may be ordinary buckets, as shown in Fig. 1, or they may be specially designed duplex or two-part buckets, as shown in
 30 Figs. 6 and 7. These buckets 29 are provided, at some point opposite the partition 28 in the nozzles, with a lug 30 which extends across the space between two adjacent buck-
 35 ets so as to confine the steam from each part of the nozzle to its own part of the bucket. These two-part buckets conduce to better efficiency when the machine is working with low pressure steam only, because said steam is confined to that part of the bucket coöper-
 40 ating with the low pressure part of the nozzle 25.

At some point in the web 16 is a port 31 controlled by a hand-operated valve 32. Under ordinary conditions, this valve will
 45 remain closed, but in case of a heavy over-
 load, it can be opened to admit the low pres-
 sure steam to the high pressure stage cham-
 ber and the lower part of the nozzles 25.

After passing through all the low pressure
 50 stages, the steam is drawn off to the con-
 denser through the conduit 33. The vacuum in the condenser influences all the low pres-
 sure stages, so that when the high pressure
 55 wheel 3 is not in use, it runs idle in a body of low pressure steam at not above atmospheric pressure, which greatly reduces the rotation losses.

In accordance with the provisions of the patent statutes, I have described the prin-
 60 ciple of operation of my invention, together with the apparatus which I now consider to represent the best embodiment thereof;

but I desire to have it understood that the apparatus shown is only illustrative, and that the invention can be carried out by other means.

What I claim as new and desire to secure by Letters Patent of the United States, is,—

1. A mixed pressure turbine having a cas-
 ing provided with a hollow head forming a 70 receiving chamber for the low pressure steam, and a segmental bridge extending across said chamber and having high pres-
 sure steam passages cored out therein.

2. A mixed pressure turbine having a cas-
 ing provided with a hollow head forming a 75 receiving chamber for the low pressure steam, and a segmental bridge extending across said chamber and having high pres-
 sure steam passages cored out therein, the 80 inner web of said head having a plurality of circumferential openings.

3. A mixed pressure turbine having a cas-
 ing provided at one end with a thick side 85 wall having low pressure steam passages cored therein.

4. A mixed pressure turbine having a cas-
 ing provided at one end with a thick side 90 wall having low pressure steam passages cored therein, and a flange at the inner end 95 of said thickened portion containing ports for exhaust steam from the high pressure stage.

5. A mixed pressure turbine having a cas-
 ing provided with a thickened wall at one 95 end and a flange, passages cored out in said wall and ports in said flange, a nozzle having two parts arranged in line respectively with said passages and ports, and a partition separating said parts.

6. A mixed pressure turbine having a cas-
 ing provided with a thickened wall at one end and a flange, passages cored out in said 100 wall and ports in said flange, a nozzle having two parts arranged in line respectively with 105 said passages and ports, and a partition separating said parts, each part of said nozzle being designed for a special volume and pressure of exhaust steam.

7. A mixed pressure turbine having pas-
 sages for low pressure steam and adjacent 110 passages for the exhaust from the high pres-
 sure stage, special two-part nozzles deliver-
 ing said steam, and a bucket wheel having 115 two-part buckets, each part receiving the steam from a corresponding part of said nozzles.

In witness whereof, I have hereunto set my hand this 8th day of August, 1913.

OSCAR JUNGGREN.
